SAFETY RAZOR

Filed May 28, 1930

UNITED STATES PATENT OFFICE

FRANK PELOSI, OF HAVERHILL, MASSACHUSETTS

SAFETY RAZOR

Application filed May 28, 1930. Serial No. 456,425.

This invention relates to safety razors and has for its principal object the provision of an improved razor of this type which comprises a relatively few parts of simple and economical construction, which permits easy and speedy insertion or removal of a separable blade, and which may be small in size and light in weight without sacrifice of operative efficiency. Further objects and specific 10 features of construction and arrangement of the improved razor will be apparent from the following description and will be pointed out in the appended claims.

A recommended embodiment of the invention is illustrated in the accompanying drawings, in which:

Fig. 1 is a front view of the improved safety razor containing a blade secured in position for use;

Fig. 2 is a rear view thereof;

Fig. 3 is a section on line 3—3 of Fig. 1, with certain parts in elevation;

Fig. 4 is a similar section showing the position of the parts when the blade is to be inserted or removed;

Figs. 5 and 6 are rear and bottom views respectively of a lock plate forming part of the razor;

Fig. 7 is a top view of a guard member 30 which cooperates with the lock plate to hold the blade in fixed position at a proper shaving angle, a portion of the blade being shown to indicate its normal disposition with respect to the guard; and

Fig. 8 is a section on line 8—8 of Fig. 7.

In the particular embodiment chosen for the purpose of illustration, the razor comprises a handle 10 having an axial opening 11 therethrough, a guard member 12 mounted in one end of the handle, a rotatable knob or lock nut 13 at the opposite end of the handle, a lock plate 14 arranged to cooperate with the guard to hold a blade 15 therebetween, and an adjusting stem 16 extending 45 through the hollow handle and having one end engaging a threaded opening 17 in the nut 13 and its opposite end passing through an aperture 18 in the guard 12 and secured to the lock plate, as by a rivet or pin 19 which projects through an opening 20 in plate 14

and is headed over on the top surface of the plate. The stem and lock plate may thus be moved longitudinally of the handle by rotating the lock nut to secure the blade in working position (Fig. 3) or to separate the plate 55 from the guard member and permit insertion or removal of the blade (Fig. 4).

In order to prevent separation of the several elements of the razor (except the blade) and hence to provide a unitary and compact 60 assemblage, inward movement of the stem relatively to the threaded lock nut 13 is preferably limited by a washer 21 which is affixed to the stem end as by a rivet 22 and which is received within an annular recess 65 23 at the outer end of the nut and seats at the bottom of said recess, when the nut is loosened as far as possible. This feature of my invention is highly advantageous in obviating possible damage to the razor elements 70 which tend to fall apart when the member connecting a group of separable parts is loosened; and the simple arrangement above described does not appreciably increase the cost of producing the razor and does not detract from the pleasing external appearance 75 of the handle.

The guard member 12 may have the usual teeth 24 and is preferably provided with strong and rigid side wings 25 which protect 80 the teeth from injury and which are preferably formed with opposed recesses 26 for receiving the forward corners of the razor blade. As best shown in Fig. 7, the rearward corners of the blade project over the wing 85 shoulders 27 so that the blade may be readily removed from the guard by lifting one of said projecting corners with a finger tip. The face of the guard member may also have an upstanding ledge 28, parallel to its toothed 90 edge, to assist in aligning the blade upon its flat seat.

The razor blade is rigidly clamped in seated position by tightening the lock nut against the end of the handle, thereby drawing the forward portion of the lock plate 14 against the upper face of the blade, so that the blade is gripped between the plate and the guard. The guard preferably has a rearwardly projecting central boss 29, and the plate is 100

provided with spaced rearward flanges 30 engaging the back of the guard on opposite sides of the projection 29, the latter being received within a complementary recess 31 between said flanges, so that the plate is held in proper cooperative relation to the guard during the adjustment of its position. To this end, the flanges 30 are sufficiently deep to engage their complementary guard surfaces when the plate is most remote from the guard, as shown in Fig. 4, thereby preventing relative rotation between the plate and guard in any position thereof.

The structural parts of the razor above described may be manufactured economically and assembled with a minimum of labor and expense. For example, the handle 10 may be made of a well known, phenolic condensation product, hard rubber or other suitable composition, in attractive colors if desired; or it may consist of a metal tube or other rigid material. The guard member 12 may be a die casting requiring no further machining operations. The lock plate 14 may be a pressed metal part of simple manufacture. And the lock nut 13, stem 16 and washer 21 are easily produced on standard automatic machines. The external surfaces of the metal parts may be nickle-plated or gilt-plated to enhance the pleasing appearance of the product. The several elements are quickly assembled as a unitary device by securing the lock plate and washer at opposite ends of the central stem, after mounting the handle, guard and lock nut thereon. A common type of flat and thin steel blade, either single or double edged, may be satisfactorily used with my improved razor. It will be apparent however that the guard and lock plate may be arranged to accommodate other types of blade while retaining the meritorious features of my invention; and that other structural details may be varied within limits without departing from the essence of this invention or defined in the following claims.

As heretofore indicated, my improved razor may be made in small sizes, particularly suitable for use by ladies in shaving at the 50 arm pits; and for such purposes the toothed edge of the guard and the blade edge may desirably be curved to conform to the contour of the underarm.

I claim:

55 1. A safety razor comprising a hollow handle, a guard member mounted at one end of the handle, a stem extending through the handle and guard, a locking plate secured at one end of the stem and cooperating with the 60 guard to hold a blade therebetween, a nut threading on the opposite end of the stem and bearing against the end of the handle to draw the plate toward the guard member 65 and clamp the blade therebetween, and means

on the stem engaging the nut to limit outward rotation of the nut.

2. A safety razor comprising a hollow handle, a guard member mounted at one end of the handle, a stem extending through the handle and guard, a locking plate secured at one end of the stem and cooperating with the guard to hold a blade therebetween, a nut threading on the opposite end of the stem and bearing against the end of the handle to draw the plate toward the guard member and clamp the blade therebetween, and a washer fixed on the stem and seating against the nut when the latter is loosened to permit removal of the blade, thereby to limit rotation of the nut. 70 75 80

3. A safety razor comprising a hollow handle, a guard member mounted at one end of the handle, a stem extending through the handle and guard, a locking plate secured at one end of the stem and cooperating with the guard to hold a blade therebetween, a nut threading on the opposite end of the stem and bearing against the end of the handle to draw the plate toward the guard member and clamp the blade therebetween, the nut having a recess in its outer end, and a washer fixed on the opposite end of the stem and seating within said recess when the nut is loosened to permit removal of the blade, thereby to limit rotation of the nut and prevent complete separation of the razor elements. 85 90 95

4. A safety razor comprising a hollow handle, a guard member mounted at one end of the handle, a stem extending through the handle and guard, a locking plate at one end of the stem and cooperating with the guard to hold a blade therebetween, a nut threading on the opposite end of the stem and bearing against the end of the handle to draw the plate toward the guard member and clamp the blade therebetween, means for limiting rotation of the nut to prevent accidental separation of the razor elements, and means associated with the guard member and locking plate for preventing relative rotation therebetween. 100 105 110

Signed by me at Boston, Massachusetts, this 26th day of May, 1930.
